UNITED STATES PATENT OFFICE

RICHARD W. CARLISLE, OF WILKINSBURG, PENNSYLVANIA, ASSIGNOR TO WESTINGHOUSE ELECTRIC & MANUFACTURING COMPANY, A CORPORATION OF PENNSYLVANIA

FIELD CONTROL DEVICE

Application filed June 29, 1928. Serial No. 289,319.

My invention relates to field-control devices and particularly to arcing-horn structures for high-voltage transmission-line insulators.

- 5 One object of my invention is to provide an arcing-horn structure that shall more nearly approach the capacitance characteristics of an arcing ring than arcing-horn structures heretofore employed.
- 10 Another object of my invention is to provide an arcing-horn structure that shall protect its insulator both at its sides above the line and at its intermediate sides and, at the same time, compensate for the presence and 15 effect of a tower or adjacent conductor opposite one or both of said intermediate sides.
- Another object of my invention is to reduce the number of points or positions on an insulator at which an arc is likely to strike 20 with an arcing horn of usual practice.

Another object of my invention is to provide an arcing-horn structure that shall combine certain of the operating characteristics of an arcing ring with certain of the economical advantages of an arcing horn.

A further object of my invention is to provide an arcing-horn or field-control device that shall be simple and durable in construction and effective in its operation.

30 In transmission-line practice, especially in connection with high-voltage suspension insulators, it has been usual to employ arcing horns and rings to keep arcs away from the insulators which the arcs are likely to damage. Also, in suspension insulators, the lower units have less capacity to ground than the upper units, thus requiring the lower units to carry a greater proportion of the 35 total voltage drop across the insulator than the upper units.

The presence of an arcing horn or ring tends to equalize the voltage gradient and to increase the minimum flashover voltage value of the insulator, but, since a ring extends 45 about the insulator axis, it has this tendency to a greater degree than a horn. However, the ring is appreciably more expensive than the horn, as well as having installation and other disadvantages not present in the horn.

50 It is my aim to provide a better arcing-

horn structure, in that it shall have certain of the advantages of an arcing ring and, at the same time, be free of the above-mentioned disadvantages of the ring, in accomplishing which end I utilize certain features of construction and operation of the field-control device of my co-pending application, Serial No. 289,320, filed June 29, 1928, to which reference may be had for a better understanding of the invention herein set forth.

Accordingly, in practicing my present invention, I provide an arcing-horn structure in which an arm or arms so extend, preferably in the direction of the line, and a shorter arm or arms so extend laterally to the first arm or arms as to improve the capacitance effect, increase the number of arc-striking points, compensate for the presence of adjacent disturbing elements, facilitate mounting, economize manufacture and provide other advantages that render the device a distinct advance in the art to which it relates.

Figure 1, of the accompanying drawings, is a fragmentary top-plan view of a device embodying my invention,

Fig. 2 is a side elevational view of the device shown in Fig 1,

Fig. 3 is a bottom-plan view of the device shown in Figs. 1 and 2, and

Fig. 4 is a slightly enlarged detail perspective view of a portion of the structure shown at the bottom of Fig. 2 and at the center of Fig. 3.

The device comprises, in general, an insulator 2, a clamp 3, at the bottom end thereof, for securing a conductor 4 thereto, an upper arcing-horn or terminal structure 5 and a lower arcing-horn structure 6.

The insulator 2, for purposes of illustration, is shown as of a usual so-called series-string type comprising dielectric bodies having disks or petticoats 8 and including metal caps 9. These elements or units also include pins of a well-known type (not shown) for connecting the units flexibly to each similar unit therebelow and to the clamp 3, the pins being connected to clevis portions 10 on the metal caps 9, and the top clevis 10 being connected to a cross arm of a tower or pole (not shown).

The clamp 3 may be of any suitable type but is preferably provided with bolts, such as U-bolts 12, for securing the conductor 4 and the bottom arcing-horn structure 6 in position.

The upper arcing-horn structure 5, of cruciform shape, comprises arms 14 extending in the general direction of, or substantially parallel to, the conductor 4, and shorter arms 15 extending transversely, or at substantially right angles to, the line conductor 4 and the arms 14. Each of the arms 14 and 15 has an inner portion 16 extending partially around the top cap 9 cooperating with the portions 16 of the other arm to substantially constitute a ring clamping structure and a portion 17 extending along a portion of the next adjacent arm to which it is clamped or secured, as by a bolt 18.

Each of the arms 14 and 15 also has a gradually-upwardly-curved portion 20 merging into a gradually return-bent top portion 21, a portion 22 extending downwardly and outwardly from the top portion 21 to a position below the clamping or supporting portion 16 and a gradually-curved outer end or tip 23.

The arms 14 and 15 may further be advantageously constructed of strap metal, whereby relatively broad cylindrical clamping surfaces are provided inside the portions 16 and, by twists 24, these broad surfaces are presented toward the lower arcing-horn structure 6.

The latter structure, also preferably cruciform and constructed of strap metal, comprises arms 25, of an integral member 26, extending in the direction of the line conductor 4 and secured to the underside of the clamp 3 by the bolts 12. From the position beneath the clamp 3, the arms 25 have portions 27 curved or bent around the conductor 4 to upwardly-and-outwardly-extending portions 28 terminating in gradually return-bent tips or ends 29.

A cross member 31 of the structure 6 is constructed and shaped similarly to the member 26 comprising the arms 25 and has arms 32 that are shorter than the arms 25.

The cross member 31 has a channeled central portion 33, as shown more clearly in Fig. 4, which closely fits the member 25 to hold the members 25 and 31 in true cruciform relation. Holes 34 in the member 25 are for the reception of the bolts 12, and registering openings 35 in the members 25 and 31 are for the reception of a bolt or screw 36, as shown in Fig. 2.

In operation, the cross arms 15 and 31 of the upper and lower horn structures 5 and 6, respectively, add capacitance, provide a greater number of arc-striking points and, since they are shorter than the arms 14 and 25, respectively, they compensate for, and

permit the closer spacing of, similar structures of adjacent parallel lines.

The construction of parts, while thus providing an arcing horn that more closely approaches the characteristics of an arcing ring than a usual horn structure, is, however, materially more economical in manufacture and easier to install, besides permitting a selection of combinations of striking points and control of the arc by permitting the ready omission of one or more of the arms.

When a weak-current discharge occurs, it strikes one of the portions 20 of the upper horn structure 5 and, having insufficient magnetic field to force it outwardly, is carried by convection, caused by its heat, to the top portion 21, where it plays back and forth until it is dissipated. When a strong-current discharge occurs, it is forced outwardly by its own magnetic field along the upper and lower horn portions 22 and 28, respectively, in either case being kept away from the insulator 2 and particularly from the top petticoat 8, as is not true of ordinary horns on weak-current discharges.

While I have shown and described a particular form of my invention, changes may be effected therein without departing from the spirit and scope thereof, as set forth in the appended claims.

I claim as my invention:

1. In combination, in a transmission-line device, an insulator and an upper arcing-horn structure therefor comprising an arm extending substantially parallel to the line and an arm extending transversely to the line, each of said arms having a supporting portion adjacent to the insulator, a portion extending upwardly from said supporting portion and a portion extending downwardly from said upwardly-extending portion to a position below said supporting portion.

2. In combination, in a transmission-line device, an insulator and an upper arcing-horn structure therefor comprising an arm extending substantially parallel to the line and a shorter arm extending transversely to the line, each of said arms having a supporting portion adjacent to the insulator, a portion extending upwardly from said supporting portion and a portion extending downwardly from said upwardly-extending portion to a position below said supporting portion.

3. In combination, an insulator, and electrodes therefor, one of said electrodes including angularly related arms extending, in general, transversely to the insulator axis, each of said arms having a supporting portion adjacent to the insulator, an intermediate portion extending from said supporting portion away from said other electrode and a portion extending from said intermediate portion toward said other electrode.

4. In combination, an insulator, and elec-

trodes therefor, one of said electrodes including angularly related arms extending, in general, transversely to the insulator axis, each of said arms having a supporting portion adjacent to the insulator, an intermediate portion extending from said supporting portion away from said other electrode and a portion extending from said intermediate portion toward said other electrode beyond said supporting portion.

5. An electrostatic-field-control device comprising spaced electrodes, one of which includes angularly related arms extending, in general, transversely to the longitudinal axis of the device, each of said arms having an inner portion adjacent to said axis, an intermediate portion extending from said inner portion away from said other electrodes and a portion extending from said intermediate portion toward said other electrode.

6. An electrostatic-field-control device comprising spaced electrodes, one of which includes angularly related arms extending, in general, transversely to the longitudinal axis of the device, each of said arms having an inner portion adjacent to said axis, an intermediate portion extending from said inner portion away from said other electrode and a portion extending from said intermediate portion toward said other electrode beyond said inner portion.

23 7. An electrostatic-field-control device comprising spaced electrodes, one of which includes angularly related arms extending, in general, transversely to the longitudinal axis of the device, each of said arms having an inner portion adjacent to said axis, an intermediate portion extending from said inner portion away from said other electrode and an outer portion extending from said intermediate portion toward said other electrode, there being a rounded portion between said inner and intermediate portions, said intermediate portion being rounded and said outer portion being rounded adjacent to its outer end.

In testimony whereof, I have hereunto
subscribed my name this 20th day of June,
1928.

50 RICHARD W. CARLISLE
